Des. 229,327
Patented Nov. 20, 1973

229,327

TOY COVERED BRIDGE

John R. Ternovan, 1712 Valley Forge Road,
Lancaster, Pa. 17603

Filed Aug. 30, 1971, Ser. No. 176,431

Term of patent 14 years

Int. Cl. D21—01
U.S. Cl. D34—15 LL

FIG. 1

FIG. 2

FIG. 3

FIG. 4

FIG. 1 is a perspective view of the toy covered bridge showing my new design.

FIG. 2 is an end elevation view, both ends being identical.

FIG. 3 is a side elevation view, both sides being identical.

FIG. 4 is a top plan view.

I claim:

The ornamental design for a toy covered bridge, as shown and described.
